UNITED STATES PATENT OFFICE.

GEORGE M. HOPKINS, OF ALBION, NEW YORK.

IMPROVEMENT IN GAS-REGULATORS FOR VULCANIZERS.

Specification forming part of Letters Patent No. 139,579, dated June 3, 1873; application filed October 19, 1870.

To all whom it may concern:

Be it known that I, GEORGE M. HOPKINS, of Albion, in the county of Orleans and State of New York, have invented certain Improvements in Apparatus for Regulating the Flow of Gas for Heating Dentists' Vulcanizers, and for other purposes, of which the following is a specification:

My invention relates to the combination of a suitable gas cut-off or stop with a steam-gage in such a manner that when the said gage shall indicate a given pressure only sufficient gas will pass through the cut-off to maintain that pressure, the object of this part of my invention being to maintain a uniform temperature in the vulcanizer, and also to prevent explosions from over pressure.

Figure 1 shows the cut-off connected with a steam-gage. Fig. 2 shows the cut-off connected with a clock. Figs. 3, 5, and 6 are different forms of stops or cut-offs. Fig. 4 represents a mercurial steam-gage with my improvement attached.

In Fig. 1, A is a steam-gage, constructed in any of the ordinary forms, provided with an adjustable index, B. C is a gas cut-off, consisting of a suitable vessel, D, partly filled with mercury or some other liquid, and closed at the top, excepting the holes through which the tubes e, f, g, and h pass. The tube f reaches just below the surface of the mercury. The tube g opens just above the mercury, and the tubes e and h open just below the top of the vessel D. j is a float, which rests upon the mercury. K is a wire, which passes down through the tube f, and is bent up and attached to the float j. It will be seen that, as the tube f opens below the surface of the mercury, the wire K has a perfect frictionless packing. The wire K passes up through an aperture in the steam-gage case, so that the adjustable index B may strike it when the index proper indicates any pressure above that which is required. g and h are inlet gas-pipes. The tubes h will allow only enough gas to pass through to keep the jet burning under the vulcanizer, while the tube g is large enough to allow sufficient gas to pass to supply the largest flame required. The outlet e is connected with a Bunsen's or other burner, which is placed under the vulcanizer. The

steam-gage A is connected by a pipe with the steam-room of the vulcanizer.

The gas is turned on at full head, and when the pressure in the vulcanizer increases so that the index B strikes the wire K, it forces the float j into the mercury, displacing a portion of it, causing it to rise, covering the mouth of the tube g, more or less, regulating the amount of gas consumed, so that a constant and even pressure is maintained. Should the tube g be entirely closed, the tube h will supply sufficient gas to support a small flame.

In Fig. 2, I is a clock, of ordinary construction, except that it is provided with an adjustable index, L. M is a cut-off, like the one shown in Figs. 1 and 3, except that the tube h is dispensed with. The wire K passes through an aperture in the clock-case, so that the index L may strike it any time at which it may be set, when the float j will be depressed, displacing the mercury, which will cover the mouth of the tube g, shutting off the gas entirely.

Fig. 4 represents an ordinary mercurial steam-gage, working with a diaphragm. The glass tube N is bent over at the top to make an outlet for the gas. An opening is made in it to receive the tube O, which is open at the bottom and has a small hole drilled in it at p. The lower end of the tube O is placed at the point q, at which it is desired to cut off the main flow of gas. The gage is connected with the steam-room of the vulcanizer, and the gas is taken in at r and out at s to supply the burner under the vulcanizer. When the pressure in the vulcanizer increases the mercury in the tube N is forced up and covers the end of the tube O. The aperture p will then allow only enough gas to pass through to supply a small flame.

Fig. 5 represents a device for cutting off the supply of gas, similar to the one represented in Fig. 1. T is a closed vessel containing mercury. u is an inlet-pipe, which is bent so that it may open upward, above the mercury. The tube f and wire K are arranged in the same manner as in Fig. 3, but the end of the wire is turned up and attached to the valve V. The valve V is made to open or close the pipe u, as the wire K is acted upon by the steam-gage or clock. w is the outlet.

Fig. 6 is a cut-off differing from the others.

x is a suitable vessel containing mercury. *y* is the small inlet-pipe; *z*, the large one. 1 is the outlet. 2 is a cup-shaped vessel inverted, of a suitable size to slide easily in the vessel *x*; it is divided by the partition 3, which does not extend down as far as the sides of the vessel. The partition 3 is placed between the pipe *z* and the pipes *y* and 1. The edges of the vessel 2 dip in the mercury, while the partition 3 does not touch it. A wire, K, is attached to the vessel 2, and is operated upon by the steam-gage in the same manner as the

wire K in Fig. 1. When the wire K is depressed the partition 3 touches the mercury, thereby shutting off the large inlet-pipe *z*, and limiting the supply of gas to the small inlet *y*.

I claim as my invention—

The combination of the gas cut-off C with the steam-gage A, substantially as and for the purpose hereinbefore set forth.

GEO. M. HOPKINS.
